DESIGN FOR A CHAIR BACK

John Gordon Rideout, Cleveland, Ohio, assignor to Calumet Manufacturing Corporation, Hammond, Ind.

Application January 30, 1939, Serial No. 82,670

Term of patent 7 years

To all whom it may concern:

Be it known that I, John Gordon Rideout, a citizen of the United States, residing at Cleveland, in the county of Cuyahoga and State of Ohio, have invented a new, original, and ornamental Design for a Chair Back, of which the following is a specification, reference being had to the accompanying drawing, forming part thereof.

Fig. 1 is a front elevational view of a chair back showing my new design.

Fig. 2 is a side elevational view thereof.

Fig. 3 is a top plan view of the chair back.

I claim:

The ornamental design for a chair back substantially as shown.

JOHN GORDON RIDEOUT.
